(57) **CLAIM**

The ornamental design for a disc cartridge, as shown and described.

DESCRIPTION

FIG. 1 is a rear, bottom left perspective view of a disc cartridge showing our new design;

FIG. 2 is a rear elevational view thereof;

FIG. 3 is a bottom plan view thereof;

FIG. 4 is a left side elevational view thereof; and,

FIG. 5 is a right side elevational view thereof.

In the drawings, the broken lines depict environmental subject matter only and form no part of the claimed design. Dot-dash broken lines define the boundaries of, but not included in, the claimed design.
